(57) **CLAIM**

The ornamental design for a bicycle tire tool or the like, as shown and described.

DESCRIPTION

FIG. 1 is a left side perspective view of a design for a mounting tool;

FIG. 2 is a right side view thereof;

FIG. 3 is a left side view thereof;

FIG. 4 is a first end view thereof;

FIG. 5 is a second opposing end view thereof;

FIG. 6 is a top view thereof;

FIG. 7 is a bottom view thereof; and,

FIG. 8 is a right side perspective view thereof.

The broken lines shown illustrate portions of the bicycle tire tool that form no part of the claimed design.

1 Claim, 4 Drawing Sheets
